APPARATUS FOR FORMING TYING STRIPS
AND APPLYING THE SAME TO BAGSAdolph Potdevin, Garden City, N. Y., assignor to
Potdevin Machine Company, Brooklyn, N. Y., a
corporation of New YorkOriginal application May 3, 1937, Serial No.
140,436. Divided and this application March
9, 1938, Serial No. 194,814

1 Claim. (Cl. 271—45)

This invention relates to improvements in machines for making bags and is particularly directed to an improved device for applying a metal tie strip to the end of bags of the type known 5 commercially as metal tie bags.

This application is a division of my copending application Serial No. 140,436, filed May 3, 1937, and is directed more specifically to a device of the character indicated having novel feeding means for the blanks in the making of such bags as above referred to.

In making metal tie bags a small strip of metal extending transversely of the bag is applied to the open end of the bag and when the bag is to be closed the strip and bag end are rolled over upon the bag several times and the projecting ends of the tie strip are bent over the bag body to hold the bag closed.

It is an object of the present invention to provide a machine which is full automatic in its operation and is adapted to form the tie strips and to apply the same to the bag in continuous operation. However, the present application is more specifically directed to the novel means for withdrawing bags from the bottom of a stack of bags and means for moving the bags laterally toward the discharge end of the machine.

In the accompanying drawings I have illustrated the machine of the present invention.

30 In the drawings:

Fig. 1 is a plan view of the machine; and

Fig. 2 is a sectional elevational view taken substantially on line 2—2 of Fig. 1.

Referring to the drawings in detail: Bags 2 are taken from a magazine formed by adjustable uprights 4 located at the charging end of the machine, and are passed through the machine continuously while traveling laterally. During the advance of the bags a metal strip 6 enclosed in paper tape 8 and constituting the tie strip is applied to the projecting flap 10 which is provided for this purpose at the open end of each bag.

The metal tape 6 and the paper tape 8 are taken from separate supply spools (not shown), the paper tape being folded about the metal strip as the two progress through the machine.

The supply bags 2 are stacked at the magazine 4 on a table or bed 16. The bags in the stack lie transversely of the machine and are fed forward lengthwise successively from the bottom of the stack with the bag bottom in the lead, into position to be picked up by the forwarding mechanism which forwards the bags laterally toward the discharge end of the machine.

55 It will be seen from Fig. 1 that the magazine

table or bed 16 is provided with an opening in the bottom thereof, the bags being disposed on this table or bed so that one flap of the bag bottom of the lowermost bag of the stack will sag downwardly through this opening.

Beneath the magazine table or bed 16 are a pair of forwarding jaws designated 22 and 24 for gripping the flap of the lowermost bag and forwarding the bag to forwarding rollers, as will be described presently. The operation of these 10 jaws 22 and 24 and the various cams controlling the same are described in full detail in my copending application Serial No. 140,436.

This mechanism, however, is so arranged that at the proper time the jaws 22 and 24 will close 15 upon the sagging flap at the bottom end of the lowermost bag in the stack of bags and then pivot in a forward direction away from the magazine to drag the end of the bag out of the stack and move it forward sufficiently for the same to be 20 engaged between a pair of forwarding rollers 50 which are mounted to rotate about axes extending lengthwise of the machine, the jaws 22 and 24 upon delivering each bag to these rollers opening and then returning to their original position 25 to receive the next bag.

The forwarding rollers 50 deposit each bag crosswise of the machine upon a table or bed 52 provided with slots 54 extending lengthwise of the machine. This table 52 is provided with a 30 side plate 56 and an end plate 58 for promoting proper positioning of the bags on the table. These plates are adjustable so as to accommodate the machine to bags of different lengths as well as to bags of different widths.

As each bag is deposited upon the table or bed 52 it is engaged by a pusher 60 which is reciprocated lengthwise of the machine by mechanism shown in my copending application Serial No. 140,436. This pusher engages the side of each bag as the same is deposited on the plate 52 to move the bag laterally lengthwise of the machine to forwarding rollers 66. The rollers 66 deliver the bags between upper and lower forwarding chains or bands designated 68 and 70, respectively.

A motor 94 is provided for driving the machine. This motor, through a sprocket and chain drive, drives a pinion 96 meshing with a spur gear 98 mounted on a stub shaft which carries a gear 100. The gear 100 meshes with gear 102 mounted on 50 shaft 104 carrying pinion 106, the latter meshing with a pinion 108 in mesh with a pinion 110 on shaft 112. The latter extends longitudinally of the machine toward the charging end thereof where the shaft terminates. This end of the 55

- shaft carries a gear 113 meshing with wide faced gear 114, the gear 114 meshing with a gear 116 on shaft 34. The opposite end of this cam shaft 34 carries a gear 118 meshing with gear 120 in mesh with gear 122 on the shaft carrying the lower roller of the two forwarding rollers 50, this shaft carrying a gear in mesh with a gear on the shaft of the upper rollers of the forwarding rollers 50, to provide a drive therefor.
- 10 The drive for the forwarding chains 68 and 70 is from a pinion 138 on the stub shaft 104, gears 140, 142, 144, bevel gears 146 and 148 which drives shaft 150 carrying the sprocket for the lower chain 70. This shaft 150 carries a gear 152 meshing with gear 154 on the shaft 156 carrying the upper chain 68. This gear train will drive the lower lead of the chain 68 and the upper lead of the chain 70 in the same direction toward the delivery end of the machine.
- 20 Referring to Fig. 2, it will be seen that the upper lead of the lower chain 70 rides along depressed tracks 160 in the machine bed 158 while the lower lead of the chain 68 rides beneath a spring-pressed plate 162 urged downwardly toward the chain 70 by springs 164. This provides for gripping the bags so as in effect to attach the bags successively to the forwarding chains for advancement.
- 25 The metal tape 6 forming part of the tie strip 30 is taken from a supply reel lying beneath the machine and the tape is drawn upwardly to the machine bed and then forward toward the discharge end of the machine by a pair of feed rolls 166. The metal tape as it is drawn upwardly 35 passes about guide rolls as shown and described in my parent application Serial No. 140,436 and the paper tape 8 which is taken from a supply reel which is to enclose the metal tape 6 before the latter is placed in position on the bags 2 is 40 also forwarded by the feed rolls 166.
- 30 The paper tape passes from a supply reel about guiding and tensioning rollers and between roller 192 and a gluing roller where three stripes of adhesive are continuously applied to the face 45 of the tape, as described in my parent application Serial No. 140,436.
- 35 The paper next passes about the rollers 180, 181 and 182. The roller 182, as will be seen from Fig. 2, is so shaped that as the paper tape passes 50 the same one edge of the tape will be turned inwardly over and upon the metal tape 6 to bring the adhesive stripe 197 into engagement with the face of the metal tape. As the paper tape and metal tape continue their forward movement 55 a stripe of adhesive 198 is applied to the turned-over part of the tape, as shown in Fig. 2.
- 40 The paper tape then passes over the roller 184, and the metal tape and the paper tape from thence travel lengthwise of the machine beneath 60 the projecting flap 10 of the bags 2, the adhesive stripe 198 contacting the underside of the flap.
- 45 As the paper and metal tapes, together with the bags, travel lengthwise of the machine they pass a plate 204 which deflects that portion of 65 the paper tape carrying one of the adhesive

stripes upon the upper face of the flap 10 of the bags. The tapes and bags then pass beneath a hinged plate 208, to the rollers 166 which press the tapes and bags together.

5 The tie strip is continuous, as will be understood, and after it has passed the rollers 166 it is cut off between adjacent bags 2 by a striker bar 214. After the tie strip has been severed the chains 68 and 70 continue the lateral advance of each bag with tie strip attached until the same 10 is picked up by discharge rollers 216 by which the bags are successively discharged into a receiving trough 218. The discharge rollers 216 are geared together and are driven off the gear 154.

15 The feed rollers 166 are driven off the gear 152 through intermediate gear 153 and gear 155.

20 The shaft 186 which carries the sprocket 188 for one end of the lower forwarding chain 70 is provided with a gear 222 meshing with a pinion 224 which in turn meshes with pinion 226 on the shaft of the lower pair of forwarding rollers 66, this gear meshing with gear 230 on the shaft of the upper pair of forwarding rollers 66.

25 It will be seen from all of the foregoing that the present invention provides an automatic machine so constructed and arranged that bags are continuously taken from a supply stack and forwarded laterally through the machine. At the same time paper tape and metal tape are continuously fed lengthwise through the machine in superimposed relation to each other, adhesive being applied to the paper before the same contacts the metal strip and the paper being wrapped about the metal, these two tapes finally being 30 brought into superimposed relation with respect to the laterally traveling bags, whereupon the paper tape is folded over and attached to the bags. Prior to the discharge of the bags from the machine the tapes, which constitute the tying 35 strip, are severed between adjacent bags so that in the finished bag we find a tying strip made up of paper and metal attached to the projecting flap on the open end of the bag with the ends of the tying strip projecting a short distance beyond 40 the sides of the bag.

45 It is to be understood that the details of construction and arrangement of parts herein shown and described may be varied without departing from the spirit and scope of my invention.

50 What I claim is:

55 In a machine of the class described, the combination of a machine bed having depressed tracks therein disposed in parallel relation, a pair of forwarding chains, the upper flight of each of said chains riding along said tracks, a pair of forwarding chains above the first-mentioned chains, and a spring-actuated plate overlying the lower flight of each of said upper chains and extending continuously substantially the 60 length of the chain to force the same into pinching or clamping position with respect to the adjacent flight of the lower chain in said depressed track, thereby to grip an article to be forwarded.

65 ADOLPH POTDEVIN.
